UNITED STATES PATENT OFFICE.

JOSEPH J. WALTON, OF NEWARK, NEW JERSEY.

CUSPIDOR.

SPECIFICATION forming part of Letters Patent No. 317,251, dated May 5, 1885.

Application filed November 10, 1884. (No model.)

To all whom it may concern:

Be it known that I, JOSEPH J. WALTON, of Newark, in the county of Essex and State of New Jersey, have invented certain new and 5 useful Improvements in Cuspidors; and I do hereby declare that the following is a full, clear, and exact description thereof, reference being had to the accompanying drawings, and to the letters of reference marked there- 10 on, which form part of this specification, in which—

Figure 1 is a side elevation of my improved cuspidor. Fig. 2 is a diametrical section through the same. Fig. 3 is a diametrical section of the case which incloses the receiving cup or vessel.

This invention relates to cuspidors; and it consists in certain novel improvements whereby they are more easily and cheaply constructed, and more easily cleaned, as will be 15 fully understood from the following description, when taken in connection with the annexed drawings.

The external contour of my spittoon or cuspidor is like that in common use—namely, a 20 globular or swelled body, A, and an upwardly-flaring or funnel-shaped mouth B. This constitutes the case of the device, which is provided with a removable dished cover, C, 25 having a hole, a, centrally through it. The bottom of this case curves inward and upward, leaving a central circular opening surrounded by a supporting-edge, b.

D designates a cylindrical receiving-cup, which is surrounded at its upper end by a 35 flaring flange, d. This cup is of greater diameter than that of the aperture a through the cover C, and the flaring flange d of the cup rests upon the annular shoulder e at the junction of the body and flaring mouth of the external case. 40

The case, and also the cup, may be made of earthenware, stoneware, metal, paper, or of any other suitable material.

Having described my invention, I claim— 45

1. The combination of the outer case, A, having an open-bottom globular body, a contracted neck, and a flaring mouth, with an internal cup, also having a flaring mouth, and a centrally-perforated dished cover, all substantially as described. 50

2. As a new article of manufacture, a cuspidor consisting of an external body or case having an open upturned bottom, a flaring mouth, and a neck forming a supporting-shoulder, in combination with an internal vessel having a flaring upper end and a dished and centrally-perforated removable cover, substantially as described. 55

In testimony that I claim the foregoing as my own I affix my signature in presence of two witnesses.

JOSEPH J. WALTON.
